UNITED STATES PATENT OFFICE.

WILLIAM E. GIBBS, OF EAST ORANGE, NEW JERSEY, ASSIGNOR TO GIBBS UTILITIES COMPANY, OF NEW YORK, N. Y., A CORPORATION OF DELAWARE.

OIL BURNER.

Application filed December 22, 1925. Serial No. 77,018.

My invention relates to that class of oil burners where the oil is introduced in a liquid state to the burner where by radiated and conducted heat it is caused to vaporize 5 while at the same time a draft of air, natural or forced, is intimately mixed with the oil vapor in such a manner that complete and efficient combustion is obtained.

There is always a tendency in such burners for the oil to form carbon deposits from 10 that part of the flame nearest the oil source where there is likely to be insufficient oxygen to insure complete combustion. As is well known, all that is necessary to produce this 15 coking action is a hot surface and unconsumed fuel in contact therewith. It is highly important therefore to keep the part 20 of the flame carrying the richest fuel mixture from coming in contact with the hot parts of the burner and the principal object 25 of my invention is to embody in a burner means for interposing between the hot surface and the heavily charged flame an intermediate stream of fresh air or else an oxidizing part of the flame.

My present invention comprises means for generating a swirling motion to the air during its passage through the burner, the swirling motion being obtained by introducing 30 the air to an elongated horizontal combustion chamber in a tangential manner, (transverse to the burner length) through one or more orifices, the air sweeping first over the interior wall of the burner before it strikes 35 the oil and then together with the oil vapor forming an interior flame kept out of contact with the wall of the combustion chamber by the incoming fresh air so that half burned oil is prevented from coming in contact 40 with the hot walls of the chamber to form carbon deposits. A further extension of the combustion chamber beyond the tangential air inlets allows the admixture and combustion to be continued, the admixture 45 and the flame continuing in a vortex with the richer mixture occupying the central core of the flame and only the oxidizing part of the flame contacting with the walls of the combustion chamber.

50 Further novel combinations will appear from the following description in connection with the accompanying drawings which represent in-

Figure 1 a vertical longitudinal broken 55 section of the burner, and

Figure 2 a vertical transverse section on line 2-2 of Figure 1.

The burner casing of the combustion chamber proper is shown at 1. I prefer to make this casing in the form of a horizontally flattened cylinder of approximate oval cross-section as shown in Figure 2, and with a slight central longitudinal depression in its top wall for a portion of its length, as shown in Figures 1 and 2. The inlet end 65 of the burner, is closed with an end wall 2 and in this end wall I provide an orifice shown at 3 through which the oil is admitted to the burner. The burner may be made in two horizontally divided halves 70 secured together by bolts 4. The burner has at its inlet end a depressed trough portion 5 for holding a pool of oil and this portion may be occupied with for example granular 75 refractory material such as sand. Extending to a suitable height in this depressed part of the burner is an overflow trap or pipe 6 through which the oil may escape into a drain 7, thus forming a means for conveying back to the oil reservoir any surplus 80 oil that may accumulate in the said depressed portion of the burner. I prefer to surround the burner with a baffle casing 8 and to place the burner with its baffle in an outside box 9 to which air may be admitted 85 through an orifice shown at 10, the construction being such that a large part of the air entering the box 9 through orifice 10 will pass forward the length of the box and return through the baffle in contact with the 90 hot walls of the burner before entering the latter. Some of the air will, however, pass from box 9 over the upper edges of the end and side walls of baffle casing 8, as indicated 95 by arrows in the drawing. The air enters 100 the burner chiefly through tangential orifices 11 located on each side of the depressed oil receptacle 5 and also through central orifices 12, both the orifices 11 and the orifices 12 being tangentially directed in the same 105 direction to give a gyratory action to the air in the flattened cylinder, the air entering at the two series of side orifices 11, passing first in contact with the upper wall of the cylinders and then meeting a downward current of air coming through the orifices 12 before it comes in contact with the oil lying in a pool in the depressed portion 5 of the burner. From contact of the air with the 110 wall and from the heat of the burner con-

veyed to the oil both by conduction and radiation, the air when it reaches the lower part of the combustion chamber picks up a certain amount of the vaporized oil and carries the same in a gyratory path which is, however, inside of the gyratory path of the incoming fresh air and is thus prevented from coming in direct contact with the hot walls of the burner or if any of it should come in such contact it would only be in the presence of an excess of air and further form a strongly oxidizing flame which would not result in any deposition of carbon. The swirling flame thus produced, when looked at endwise, shows a central core heavily charged with fuel, the outside of the flame being clear. The orifices 12 are in the center of the double arch or depressed portion of the top wall of the flattened cylindrical casing. Both the orifices 11 and 12 only extend part way along the burner preferably about as far as the depressed portion 5. From there on in the part indicated at 13 the burner may have an elliptical or any other suitable cross section, for here while the whirling or gyratory motion continues forming a double vortex-like current, the admixture is further completed and total combustion insured. Oil is admitted through pipe 14 to the box 9 where it may drop upon the top of the burner casing in a pocket formed by flange 15 and running over the edge of a shelf 16 may fall to the bottom of a preliminary chamber 17 in the bottom of which there may be also a refractory wick 18. From here the oil will pass through the orifice 3 and disseminate itself through the wick 19 in the depressed portion 5 of the burner. Should the oil flow too fast, any surplus will escape through the trap 6 as before described. A certain amount of air will pass over the top of the baffle casing 8 and into the oil pocket 17 and thence through the orifice 3. To start the burner I provide a door or lid 20 which when opened permits the introduction of a lighted taper to start the ignition.

I claim:—

1. An oil burner comprising a horizontal casing having concave side walls, a discharge opening at one end, an oil containing pocket in the bottom wall, and air supply ports entering said casing tangentially to said concave walls in planes transverse to said casing, whereby the air is caused to sweep with a gyratory motion over the interior of the casing walls before striking the oil in said pocket.

2. An oil burner comprising an elongated horizontal burner casing of elliptical cross-section presenting curved inner, side and top walls, said casing having a discharge opening at one end, an oil containing pocket in its bottom wall, and air supply ports entering the casing tangentially to its walls

in planes transverse to the casing, whereby the air is caused to sweep with a gyratory motion over the interior of the casing walls before striking the oil in said pocket.

3. An oil burner comprising an elongated horizontal burner casing of approximately elliptical cross-section presenting curved inner, side and top walls, said casing having a discharge opening at one end, an oil containing pocket in its bottom wall, and air supply ports entering the casing tangentially to its walls upon both sides of said oil containing pocket in planes transverse to the casing, whereby the air is caused to sweep with a double vortex over the interior of the casing walls before striking the oil in said pocket.

4. An oil burner comprising an elongated horizontal burner casing of elliptical cross-section having a central depression in its top wall for a portion of its length, a discharge opening at one end, an oil containing pocket in the bottom beneath said central depression, means for supplying oil to said pocket, and tangential air inlets extending through said casing in position to direct streams of air against the inner casing walls and subsequently over the oil in said pocket.

5. An oil burner comprising a horizontal cylindrical casing having an end wall and a recess at the bottom adjacent to said end wall, said recess containing a porous refractory wick, and tangential air orifices in the wall of said casing through which air entering the casing is directed first against the wall of the casing opposite the wick to protect said opposite wall from carbon deposition.

6. An oil burner comprising a horizontal casing having curved side walls and an end wall forming a combustion chamber, an oil containing recess in the bottom of said combustion chamber adjacent to said end wall, means for supplying oil to said recess, said end wall having an opening through which air may be permitted to flow into said combustion chamber, and tangential air inlets extending through the casing so as to direct streams of air first against the sides of the casing and then on to the oil in said recess.

7. An oil burner comprising a horizontal casing having an end wall, means for holding oil in said casing, and tangential air inlets through the casing so as to direct the air stream first against the sides of the casing and then onto the oil, a preliminary oil receiving pocket adjacent to said end wall, and said end wall having an opening therethrough, permitting oil and air to flow from said pocket into the combustion chamber.

8. An oil burner comprising a horizontal casing having an end wall, tangential air inlets through the casing so as to direct the air stream first against the sides of the casing and then onto the oil, an oil receiving

- 5 pocket adjacent to said end wall, and said end wall having an opening therethrough, permitting oil and air to flow from said pocket into the combustion chamber, and a removable lid for said receiving pocket.
9. An oil burner comprising an elongated horizontal burner casing having a wall at one end and an oil receptacle at the bottom adjacent said end wall, the top of the casing being arched above said receptacle, and tangential inlets through the casing at the sides of the oil receptacle.
10. An oil burner comprising a horizontal burner casing having a wall at one end and an oil receptacle at the bottom adjacent said end wall, the top of the casing being double arch shaped, and tangential inlets through the casing at the sides of the oil receptacle.
11. An oil burner comprising a horizontal burner casing having a transverse wall at one end and an oil receptacle at the bottom adjacent said end wall, the top of the casing being arched above said oil receptacle, tangential inlets through the casing at the sides
- 15 of the oil receptacle, and other air inlets 25 through the arched top of the casing.
12. An oil burner comprising a horizontal burner casing having a wall at one end and an oil receptacle at the bottom adjacent said end wall, the top of the casing being double 30 arch shaped, tangential inlets through the casing at the sides of the oil receptacle, and other air inlets through the double arched top of the casing.
13. An oil burner comprising a horizontal 35 casing, having an end wall, means for admitting and holding oil in said casing, and tangential air inlets through the casing so as to direct the air stream first against the sides of the casing and then onto the oil, a 10 box surrounding the said combustion chamber open at the front end and closed at the rear, and a baffle between said combustion chamber casing and said box providing an 15 air space through which the air entering the burner must first pass along the outside of the said combustion chamber casing.
